(57) CLAIM

The ornamental design for a clothes carrier, as shown and described.

DESCRIPTION

FIG. 1 is a perspective view of a clothes carrier in an opened condition, embodying my new design;

FIG. 2 is a front elevational view thereof;

FIG. 3 is a bottom planar view thereof;

FIG. 4 is a rear elevational view thereof;

FIG. 5 is a top planar view thereof;

FIG. 6 is a left side elevational view thereof;

FIG. 7 is a right side elevational view thereof;

FIG. 8 is a perspective view of an alternative embodiment of my clothes carrier, wherein the clothes carrier is shown in a collapsed condition;

FIG. 9 is a right side elevational view thereof;

FIG. 10 is a left side elevational view thereof;

FIG. 11 is a front elevational view thereof;

FIG. 12 is a rear elevational view thereof;

FIG. 13 is a top planar view thereof; and,

FIG. 14 is a bottom planar view thereof.
